DESIGN FOR A BEVERAGE DISPENSER

Archibald R. Burgess, St. Louis, Mo., assignor to
AMP Corporation, St. Louis, Mo., a corporation
of Missouri

Application October 30, 1946, Serial No. 134,393

Term of patent 14 years

(Cl. D2—3)

To all whom it may concern:

Be it known that I, Archibald R. Burgess, a citizen of the United States, residing in the city of St. Louis, State of Missouri, have invented a new, original, and ornamental Design for a Beverage Dispenser, of which the following is a specification, reference being made to the accompanying drawing, forming a part thereof, in which Figure 1 is a top plan view of a beverage dispenser embodying my new design, Figure 2 is a side elevational view thereof, Figure 3 is a bottom plan view thereof, Figure 4 is a front elevational view thereof, and Figure 5 is a rear elevational view thereof.

I claim:

The ornamental design for a beverage dispenser, substantially as shown.

ARCHIBALD R. BURGESS.
